JOHN SHARP, OF SAN BERNARDINO, CALIFORNIA, ASSIGNOR OF ONE-HALF TO
CLIFFORD A. GREENLEAF, OF SAN BERNARDINO, CALIFORNIA.

LOCK-SEAL BOTTLE.

1,081,156.

Specification of Letters Patent.

Patented Dec. 9, 1913.

Application filed February 19, 1913. Serial No. 749,414.

To all whom it may concern:

Be it known that I, JOHN SHARP, a citizen of the United States, residing at San Bernardino, in the county of San Bernardino and State of California, have invented a new and useful Lock-Seal Bottle, of which the following is a specification.

The invention relates to improvements in lock seal bottles.

10 The object of the present invention is to improve the construction of lock seal bottles and analogous receptacles, and to provide a simple, inexpensive and efficient receptacle of this character, adapted to be easily sealed, 15 and capable of effectually preventing access to its contents without breaking the lock seal and clearly indicating the fact that the same have been broken, thereby effectually preventing any fraudulent refilling of a bottle and resale of the same as an original package.

With these and other objects in view, the invention consists in the construction and novel combination of parts hereinafter fully 25 described, illustrated in the accompanying drawing, and pointed out in the claims here-to appended; it being understood that various changes in the form, proportion, size and minor details of construction, within the 30 scope of the claims, may be resorted to without departing from the spirit or sacrificing any of the advantages of the invention.

In the drawing:—Figure 1 is a vertical sectional view of the neck of a bottle provided with a lock seal, constructed in accordance with this invention and showing the same before the seal is broken. Fig. 2 is a vertical sectional view on the line 2—2 of Fig. 1. Fig. 3 is a vertical sectional view 40 of the neck of the bottle, the seal being broken, the locking spring removed and the elastic sleeve partially rotated to cover the opening resulting from the breaking of the seal. Fig. 4 is a horizontal sectional view 45 on the line 4—4 of Fig. 3. Fig. 5 is a detail perspective view of the upper end of the neck. Fig. 6 is a detail perspective view of the stopper. Fig. 7 is a similar view of the sleeve.

50 Like numerals of reference designate corresponding parts in all the figures of the drawing.

In the accompanying drawings in which is illustrated the preferred embodiment of 55 the invention, 1 designates the neck of a

bottle or analogous receptacle, provided at one side at a point below its upper edge with an interiorly arranged circular socket 2 and having at the opposite side an alined opening 3, extending through the wall of the 60 neck and covered by an exteriorly arranged frangible shell or seal 4, adapted to be broken to expose one end of a coiled spring 5 to permit the removal of the latter, which retains a stopper 6 within the neck 1. The 65 coiled spring constitutes a resilient locking device, and it extends through a transverse opening 7 in the stopper and through opposite transversely alined openings 8 of a sleeve, 9, constructed of cork or any other 70 suitable material, which will not affect or be affected by the contents of the bottle. Any other suitable resilient locking device may, of course, be employed for securing the stopper and the sleeve within the neck of 75 the bottle.

The stopper 6, which is designed to be constructed of glass or similar material, is provided at its upper or outer end with a circular head 10, extending over the upper edges of 80 the neck and covering the same and effectually preventing access to the sleeve and the locking device from the upper or outer end of the neck, as clearly illustrated in Figs. 1 and 2 of the drawing. The head, 85 which caps the bottle, will prevent the locking device from being tampered with from the interior, so that it will be necessary to break the frangible shell or covering 4 in order to obtain access to the bottle. The 90 sleeve, which surrounds the stopper, forms a liquid tight packing to enable the bottle to be securely corked and sealed, and the stopper and the sleeve are of a length to extend below the recess 2 and the opening 95 3, so that the contents of the bottle are not exposed by the breaking of the frangible shell 4, which forms a cover for the opening 3.

It is necessary to remove the stopper when 100 it is desired to pour out the contents of the bottle, and in order to prevent any of the contents from passing through the opening 3, the sleeve 9 is partially rotated to carry an imperforate portion thereof to the said 105 opening. In order to effect this result, the sleeve is provided in its upper portion with opposite recesses 11, extending downwardly from the upper edges of the sleeve and receiving projecting lugs 12 of the stopper 6. 110

The lugs, which are formed integral with the stopper, are located at the lower face of the head 10 and project laterally from opposite sides of the stopper. The stopper is 5 interlocked with the sleeve by the lugs and the recesses, and it is adapted to be turned to rotate the sleeve, the head 10 forming a continuous grip or handle for turning the stopper. After the opening 3 has been 10 covered or closed by an imperforate portion of the sleeve, the stopper is removed and the contents of the bottle may be decanted therefrom in the ordinary manner.

While the bottle is not a nonrefillable 15 bottle in the sense that it cannot be refilled, yet the lock seal will afford ample protection against fraudulent refillings, as it is necessary to break the frangible shell or portion covering the opening 3 in order to withdraw 20 the stopper, and it will therefore be impossible to refill and restore the bottle to its original condition, as the broken frangible portion will clearly indicate the fact that it has been opened.

25 The frangible shell or covering for the opening 3 may be molded, blown or formed in any other suitable manner, and is, of course, provided on the bottle before the same is filled and corked. It covers the 30 opening 3 and constitutes an outer wall for the same and forms a recess or socket for engaging with one end of the coiled spring.

In corking the bottle, the sleeve is placed 35 on the stopper with its openings 8 in alignment with the opening 7 of the stopper. The spring is then placed in the openings 7 and 8, and in order to enable it to be readily compressed into the neck of the bottle, the latter is provided at the upper 40 edges of its neck with opposite outwardly tapered recesses 13, presenting beveled or inclined faces 14 to the ends of the spring. The spring is compressed within the openings 7 and 8 in introducing the stopper and 45 the sleeve into the neck of the bottle, and it is adapted to expand and automatically engage the opposite sockets when brought into alignment with the same, and when the spring is engaged with the said sockets, it 50 securely retains the stopper and the sleeve within the neck of the bottle.

What is claimed is:—

1. A device of the class described including a receptacle having a neck provided with 55 opposite interiorly arranged sockets and having a frangible portion constituting the outer wall of the socket, a stopper provided

with an opening, a sleeve arranged on the stopper and having opposite openings registering with the opening of the stopper, and 60 a resilient locking device extending through the openings of the stopper and the sleeve and expansible to engage the interior sockets of the neck and adapted to be removed by breaking the said frangible portion, said 65 stopper and sleeve having coacting portions, whereby the sleeve is adapted to be rotated by the stopper to carry an imperforate portion of the said sleeve to the frangible portion when the locking device is removed. 70

2. A device of the class described including a receptacle having a neck provided with interiorly arranged sockets and having a frangible portion constituting the outer wall of one of the sockets, a stopper provided 75 with an opening and having a projecting head and provided beneath the same with a lug, a sleeve surrounding the stopper and having opposite openings to register with that of the stopper and provided in its upper edge with a recess receiving the lug of the stopper, whereby the sleeve is adapted to be rotated by the stopper to carry an imperforate portion of the former opposite the frangible portion of the neck, and a resilient 80 locking device extending through the openings of the stopper and the sleeve and adapted to engage the recesses of the neck.

3. A device of the class described including a receptacle having a neck provided with 90 an interiorly arranged socket and having a frangible portion constituting the outer wall of the socket, a stopper provided with an opening, a sleeve arranged on the stopper and having an opening registering with the 95 opening of the stopper and with the said socket, a resilient locking device arranged in the opening of the stopper and the sleeve and engaging the said socket and being of a size to permit it to be removed through the 100 socket when the outer wall thereof is broken, said stopper and sleeve being provided with coacting interlocking parts, whereby the sleeve is adapted to be rotated by the stopper to carry an imperforate portion of the sleeve 105 to the said socket to cover the same when the locking device is removed.

In testimony, that I claim the foregoing as my own, I have hereto affixed my signature in the presence of two witnesses.

JOHN SHARP.
